Primary Examiner — John Windmuller*Assistant Examiner* — John R Yeh(74) *Attorney, Agent, or Firm* — Hodgson Russ LLP(57) **CLAIM**

The ornamental design for a swimming pool brush, as shown and described.

DESCRIPTION

FIG 1. is a front perspective view of a swimming pool brush showing my new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top view thereof; and,

FIG. 7 is a bottom view thereof.

The broken lines illustrate unclaimed portions of the swimming pool brush that form no part of the claimed design.

1 Claim, 6 Drawing Sheets(56)
